Patented Oct. 3, 1922.

FIG. 2

P. A. Miller Inventor

By Ode B. Billman Atty.

UNITED STATES PATENT OFFICE.

BYRON A. MILLER, OF MANSFIELD, OHIO.

MACHINE GUARD.

Application filed June 24, 1920. Serial No. 391,281.

To all whom it may concern:

Be it known that I, BYRON A. MILLER, a citizen of the United States, residing at Mansfield, in the county of Richland and State of Ohio, have invented certain new and useful Improvements in Machine Guards, of which the following is a specification.

My invention relates to improvements in machine guards, and more particularly to that class or type known as "safety press guards" particularly designed and adapted for use in connection with power shears, presses, and the like.

This invention relates more particularly to means for preventing a power shears or press from operating to move or close the knife or die carrying movable member before the operator has removed his hand from between such knife or die, as the case may be, and the subjacent or relatively fixed press or bed member thereby insuring safety and avoiding accidents.

The primary object of the invention is to provide a generally improved safety guard of this class which will be exceedingly simple in construction, cheap of manufacture, and efficient in use.

A further object is to provide a safety guard of this class which may be readily attached to or detached from any ordinary power machine of the power shear type, and which will not in any way interfere with the ordinary operation of the same.

A still further object is to provide an improved device of this character which will be operated easily and positively without unduly long movement or extra exertion, and which will necessitate the complete removal of the operator's hand from beneath the shear before the clutch can be thrown in and to hold the clutch operating means until the guard is in protected position and to operate such clutch operating means only by completely closing the guard.

A still further object is to provide a guard which will not obstruct or interfere with the use of the shear for all purposes, and which will not only normally not obstruct the line of vision of the operator but will enable the power machine to be operated in the usual manner.

With the above mentioned and other ends in view, the invention consists in the novel construction, arrangement, and combination of parts hereinafter described, illustrated in

one of its embodiments in the accompanying drawings, and particularly pointed out in the appended claims.

Referring to the drawings, forming a part 60 of this specification, Figure 1 is a front elevation of the improved guard applied to a machine of the power shear type, the guard and guard operating mechanism being in open or released position for feeding and 65 prior to the actuation of the machine clutch trip mechanism.

Fig. 2, a front elevation of the same in closed or guard forming position.

Fig. 3, a fragmentary side elevation of 70 the machine clutch actuating lever mechanism, and illustrating in particular the connection of the guard mechanism with the same.

Similar numerals of reference designate 75 like parts throughout all the figures of the drawings.

The improved guard is adapted to be attached to a power shear machine of any ordinary form or type, and the frame of the machine may be of any suitable form embodying the usual relatively fixed member or bed 1, and the relatively movable knife member 2.

The guard supporting and actuating mechanism may extend entirely across the 85 face or feed portion of the machine, as shown in Figs. 1 and 2 of the drawings.

As a means of conveniently and quickly attaching the improved guard to or removing the same from the relatively fixed portions or frame of the machine, a suitable supporting bracket 3, is provided, said bracket 3, in the form shown in Figs. 1 and 2 of the drawings, extending across the face of the machine frame and above the mouth 95 or feed portion thereof and being connected at opposite ends on suitable machine frame lugs or brackets 1^a, by means of attaching bolts 3^a.

The guard 4, may be of any suitable and 100 convenient form, and is adapted to be reciprocated into and out of the path of the material to be fed and in front of the movable member such as the shear or cutter 2, by means of suitable guard carrying and 105 actuating mechanism, said mechanism consisting, in the present instance, of guard carrying lever mechanism comprising, in the form shown in Figs. 1 and 2, two levers 5.

Referring now particularly to the form 110 shown in Figs. 1 and 2 of the drawings, it will be seen that the levers 5, are pivotally

connected to the support 3, by means of pivot bolts 6, and the upper ends of the levers 5, are connected to a cross arm or link 7.

As a means of normally holding the guard 4, and guard carrying and actuating levers 5, out of the path of the material to be fed or the mouth of the machine, a spring 8, is provided, said spring, in the present instance, being connected to the link 7, at one end, and to the supporting bracket or bar 3, at the other.

As a means of connecting the guard 4, and guard carrying and actuating levers 5, with the clutch operating foot lever 9, whereby such guard will be operated simultaneously with the movements of said lever, and whereby such guard will be thrown into guard forming position upon the actuation of the clutch mechanism for operating the relatively movable shear carrying member of the machine and upon the initial movement of the latter, the link 7 is provided with a connecting link 10, connected to a bell crank 11, pivotally connected, in the present instance, to the relatively fixed portion of the machine frame by means of a pivot bolt 11^a, one end of said bell crank 11 being connected to a vertically extending arm or link 12, the latter being connected at its lower end by means of an attaching or bearing bolt 12^b, at the side of the foot lever, as shown most clearly in Fig. 3 of the drawings.

Having thus described one of the embodiments of my invention, what I claim and desire to secure by Letters Patent, is,—

1. In a guard for power machines, a machine frame including relatively fixed and movable members, an attaching bracket attached to a stationary portion of the machine frame and extending across the face thereof and above the feed portion leading to said movable machine member, a lever pivotally mounted on said bracket and depending across the feed portion thereof, a guard member carried by said lever and adapted to be moved into and out of the feed path of said machine, a link connected to the upper end of said lever, a crank arm con-

nected to said link, a spring connected to said link for normally holding the same and said guard and guard carrying lever out of guard forming position, means for operating said movable machine member, a clutch operating trip lever at the side of said machine frame for causing the actuation of said movable machine member, and a link extending between said crank arm and clutch operating trip lever whereby said guard and guard operating mechanism will be actuated and thrown into guard forming position on the initial actuation of said clutch and movable machine member operating mechanism.

2. In a guard for power machines, a machine frame including relatively fixed and movable members, an attaching bracket attached to opposite sides of said machine frame and extending across the face thereof and above the feed portion leading between said movable and relatively fixed members, levers pivotally mounted on said bracket and having their free ends depending across the feed portion thereof, a horizontal guard member carried by and connecting the free ends of said levers and adapted to be moved into and out of the feed path of said machine, a link connected to the upper ends of said levers, a second link connected to said link, a crank arm connected to said second link, a spring connected to said first link and bracket for normally holding said guard and guard carrying levers out of guard forming position, means for actuating said movable machine member, a clutch operating trip lever at the side of said machine frame for causing the actuation of said movable machine member, and a link extending between said crank arm and clutch operating trip lever whereby said guard and guard operating mechanism will be actuated and thrown into guard forming position on the initial actuation of said clutch mechanism and said machine operating mechanism.

In testimony whereof I have affixed my signature.

BYRON A. MILLER.
